US0D1061854S

(12) United States Design Patent (10) Patent No.: US D1,061,854 S
Hu et al. (45) Date of Patent: * Feb. 11, 2025

(54) DESKTOP FAN

(71) Applicant: Shenzhen Xiaohei Technology Electronics Co., Ltd., Shenzhen (CN)

(72) Inventors: Changcai Hu, Liangshan Yi Autonomous Prefecture (CN); Tiejun Xu, Liling (CN)

(73) Assignee: Shenzhen Xiaohei Technology Electronics Co., Ltd., Shenzhen (CN)

() Term: 15 Years

(21) Appl. No.: 29/948,763

(22) Filed: Jun. 23, 2024

(51) LOC (15) Cl. 23-04

(52) U.S. Cl. D23/382
